UNITED STATES PATENT OFFICE.

LADISLAUS ZACHARA, OF SANDPOINT, IDAHO.

MATCH-BOX.

992,930.

Specification of Letters Patent. Patented May 23, 1911.

Application filed April 22, 1910. Serial No. 556,910.

To all whom it may concern:

Be it known that I, LADISLAUS ZACHARA, a citizen of the United States, residing at Sandpoint, in the county of Bonner and State of Idaho, have invented certain new and useful Improvements in Match-Boxes; and I do hereby declare the following to be a full, clear, and exact description of the invention, such as will enable others skilled in the art to which it appertains to make and use the same.

My invention relates to new and useful improvements in match boxes and my object is to provide means for dispensing the matches from the box one at a time.

A further object is to provide means whereby a match may be obtained from either end of the box and from either face thereof.

20 A further object is to provide means for limiting the movement of the match dispensing mechanisms.

A further object is to so arrange said limiting means whereby but one of the dispensing mechanisms will be open at a time.

A further object is to provide means for rotatably mounting the box upon a stand.

A further object is to provide an automatic feed for the matches.

30 A further object is to provide means whereby a view of the interior of the box may be had, and, a further object is to provide a receptacle for ashes, etc., in the base of the support for the box.

35 Other objects and advantages will be hereinafter referred to and more particularly pointed out in the specification and claims.

In the accompanying drawings which are made a part of this application, Figure 1 is 40 a vertical longitudinal sectional view through the match box and supporting stand therefor. Fig. 2 is a detail plan view of one end of the box, and, Fig. 3 is a detail sectional view through a portion of the support for the box.

45 Referring to the drawings in which similar reference numerals designate corresponding parts throughout the several views, 1 indicates the box or receptacle, which is 50 preferably rectangular in general outline and is provided with end sections 2, which are preferably removably secured to the ends of the box, so that access may be had

for filling the box with matches 3. Instead, however, of having the ends of the box removable, the walls of the box proper may be provided with swinging sections (not shown) for the purpose of filling the box. The matches are held adjacent the ends of the box and are gradually fed thereagainst by means of plungers 4, said plungers being two in number and are moved toward the ends of the box by placing a spring 5 between the plungers, the ends of the spring being fastened thereto.

55 In order to obtain a view of the interior of the box at any and all times, the end walls 2 are provided with openings 6, which may be covered with any suitable transparent substance 7, which will prevent the matches 60 from passing through the openings.

Surrounding the box 1 is a casing 8, the side walls of the casing being joined together adjacent their longitudinal centers by means of strips 9, thus leaving the opposed 75 faces of the casing open to receive dispensing plates 11 and 12, said plates being arranged in pairs and at opposite ends of the box. The plates 11 and 12 are adapted to slide between the side walls of the casing 80 and are held in position on the box by means of straps 13, said straps extending over the plates and having their ends engaged with the side walls of the casing. The inner ends of the upper and lower plates are connected 85 together by means of links 14 extending between the strips 9 and the faces of the box 1, the ends of the links being extended at right angles and entered through slots 15 and 16 in the plates 11 and 12, the outer ends 90 of the angular extensions of the links being provided with cross bars 17, which are greater in length than the width of the slots and serve to hold the links in engagement 95 with the plates. The slots 15 and 16 are so constructed that when one of the dispensing plates is extended, as shown by dotted lines in Fig. 1, the plate in alignment with the extended plate will be positioned inwardly, so that should said inwardly positioned plate be moved outwardly, the opposite plate 100 will be moved inwardly, thus permitting but one of the plates to be extended at the same time. These slots are also so arranged with respect to the links that all of the plates can 105 be in their inward positions simultaneously.

The outer ends of the plates 11 and 12 are provided with gutters 18, the depth of said gutters being such as to receive and retain a match when deposited therein, the 5 ends of the gutters having globular depressions 19 to receive the heads of the matches. These gutters, when the plates are in their inward positions, register with ways 20 in the face walls of the box, said ways being 10 of such width as to prevent more than one match to pass therethrough at the same time, thereby feeding the matches into the gutters individually and successively. After the match has been deposited in the gutter, the 15 plate is moved outwardly until the match is exposed, said plates being readily operated by attaching tabs or thumb pieces 21 thereto.

In order to provide means whereby the match may be readily grasped and removed 20 from the gutter when the plate is moved outwardly, cavities 22 are formed in the plates, approximately at the longitudinal center of the gutters, said cavities permitting the introduction of the thumb and finger on opposite sides of the match.

The box and parts attached thereto are preferably mounted between standards 23, which standards are rotatably mounted upon a platform 24 carried by a base 25, whereby 30 the box may be rotated in a horizontal plane when desired and in either direction. The upper ends of the standards 23 terminate in heads 26, to which heads are rotatably secured disks 27, the faces of said disks having 35 knobs 28 struck therefrom, which engage sockets 29 in the heads 26 to normally hold the box in a horizontal position. It will be readily seen, however, that when downward pressure is directed on either end of the box, 40 the knobs will release from the sockets, when the box may be rotated in a vertical plane and thus position either face of the box upwardly.

As this form of match box is primarily 45 used by smokers, the base 25 may be provided with a receptacle 30 to receive ashes, burned matches, etc., said receptacle being slidably mounted in the base and is removed from view when seated within the base.

In re-supplying the box with matches, the 50 plungers 4 are first depressed and the matches placed in the box, when said plungers will serve to gradually feed the matches outwardly as they are removed from the box.

The standards 23 are arranged to direct a 55 sufficient inward pressure against the sides of the casing 8 as to normally hold the box in position between the standards, but in order to positively retain the box in position, 60 the inner faces of the disks 27 may be provided with prongs 31, which prongs enter the side walls of the casing and cause the disks to rotate with the box when the box is rotated.

While I have shown and described the 65 present invention as being used for dispensing matches, it will be readily seen that the device can be used for dispensing various articles, such as cigarettes, cigars and the like, the only change from the present construction being the enlargement of the gutters in the plates and the ways in the box.

It will thus be seen that I have provided means whereby matches will be dispensed from the box one at a time and it will likewise be seen that said matches may be obtained from either face of the box. It will further be seen that the matches will be gradually fed toward the discharging openings in the box. It will likewise be seen that by mounting the box on the supporting frame, as shown, said box can be swung in either a vertical or horizontal plane and further by providing the knobs and sockets, the box will be normally held in a horizontal 85 position.

What I claim is:

1. In a gravity feed dispensing device, including a reservoir having feed openings at opposite ends, dispensing trays slidably mounted on each end and a link slidably secured to the trays, whereby said link will limit the relative positions of the trays, thus preventing their simultaneous operation and retaining one in an operative position. 95

2. A dispensing device, comprising a reservoir, means for dispensing the contents of said reservoir at either end thereof, dispensing trays at each end of said reservoir, and a link connecting said trays to limit the 100 movement thereof, whereby one will always remain in operative position.

3. A dispensing device, comprising a reservoir, means at each end of its upper and lower sides for dispensing the contents of 105 said reservoir, means to rotate said reservoir in either direction, and independent delivery trays at each end of said reservoir.

4. A dispensing device, comprising a reservoir, means at each end of its upper and 110 lower sides for dispensing the contents of said reservoir, means to rotate said reservoir in either direction, independent delivery trays at each end of said reservoir, and a link connecting each pair of trays to limit 115 the movement thereof, whereby one of the same will always remain in operative position.

5. In a gravity feed dispensing device, a reservoir having feed openings in each end 120 thereof, spring-pressed dispensers within said reservoir adapted to force the contents to said openings, means to rotate said reservoir in either direction dispensing trays 125 slidably mounted on said reservoir below the openings, and means whereby one of said trays will always be in operative position.

6. A dispensing device, comprising a res-

ervoir, independent dispensing means at each end of said reservoir, dispensing trays slidably mounted at the ends thereof, each of said trays being provided with a slot, and 5 a link connecting said slots to limit the movement of said trays, whereby one of said trays will always be in operative position.

In testimony whereof I have signed my name to this specification in the presence of two subscribing witnesses.

LADISLAUS ZACHARA.
